UNITED STATES PATENT OFFICE.

HARRY HUMPHREYS, OF LANCASTER, PENNSYLVANIA, ASSIGNOR TO ARMSTRONG CORK COMPANY, OF PITTSBURGH, PENNSYLVANIA, A CORPORATION OF PENNSYLVANIA.

DESIGN FOR LINOLEUM, OIL-CLOTH, OR FLOOR-COVERING.

43,220.

Specification for Design.

Patented Nov. 5, 1912.

Application filed September 23, 1912. Serial No. 721,982. Term of patent 7 years.

To all whom it may concern:

Be it known that I, HARRY HUMPHREYS, a subject of George V, King of Great Britain, and a resident of Lancaster, in the county of Lancaster and State of Pennsylvania, have invented a new, original, and ornamental Design for Linoleum, Oil-Cloth, or Floor-Coverings, of which the following is a full, clear, and exact description, reference being had to the accompanying drawing, forming part of this specification.

The figure is a plan view of a piece of linoleum embodying my design.

I claim:

The ornamental design for linoleum, oil cloth or floor covering as shown.

HARRY HUMPHREYS.
